PORTABLE DRAFTING TABLE

Oswald Fisher, Manchester, Conn.

Application November 25, 1932, Serial No. 644,264

4 Claims. (Cl. 33—80)

My invention relates to improvements in drafting tables, which may be easily transported from place to place.

One of the objects of my invention is to provide a novel drafting table for home, class-room and field work, which is simple and inexpensive, that may be adjusted for a convenient working posture, will insure accuracy, increase personal efficiency and may be collapsed to a very neat package for convenience in carrying and storing.

The novel features of my invention are hereinafter fully described and claimed.

In the accompanying drawings which illustrate my invention:

15 Figure 1 is a plan view of the adjustable drafting table set up in a working position.

Figure 2 is a side elevation thereof.

Figure 3 is an enlarged detail of one end of the straight edge.

20 Figure 4 is a plan of the back of the drafting table with the legs collapsed.

Figure 5 is a view looking at the top edge of the table in condition for storing or transporting.

25 Figure 6 is an enlarged section on line 3—3 of Figure 4.

Figure 7 is an enlarged section on line 2—2 of Figure 4. Similar characters of reference designate similar parts in the different views.

30 The drafting table comprises a wood top 4 and adjustable legs 5 and 6. The top 4 has in its back surface grooves 7, 8, 9 and 10 completely housing the harness arrangement to which the straight edge 11 is secured and retained in a parallel position in relation to table edge as the 35 straight edge slides over the table top.

The drafting board top, as shown in Figures 1, 2, 4 and 5 consists of several pieces tongued, grooved and glued with end cleats 12 tongued, grooved and glued thereto. On one long edge 40 and near the corners of the top are fastened with screws two metal brackets 13 and 14, in which are pivoted the adjustable wood legs 5 and 6. These legs are free to turn in said 45 hangers about the screws 15 and 16 and be clamped in alinement with the top, or in any angular 50 position from the top edge within the limits of the slot 17 in the leg 5, by the thumb nut 18, bolt 19 and washer 20. The slot 17 in the leg 5 is of a width to permit the free movement of the clamping bolt 19, thus not only allowing a 55 free sliding action, but also a slight side motion at any point of the slot so that the legs may be set at various angles to each other, to bring the bearing seats of the legs at different distances from the top edge of the table and readily find-

ing a good four point bearing when the table is mounted on an uneven surface.

The top has secured on the corner of the edge, opposite to the leg mountings, two pieces of cushioning material, such as pebbled rubber 21, these forming soft bearing seats. The same material may be fastened to the leg ends 22, to form a non-slipping rest that will not injure any highly polished finished furniture, upon which the table may happen to be placed.

10 The straight edge 11, Figures 1, 3 and 4, consists of a bevel edged piece of suitable wood secured at each end to a spacing block 23 by the screws 24. The block 23 has fastened to its lower surface the harness cord anchor plates 25. As 15 shown in Figures 3 and 4, the cord 32 is threaded through the countersunk guide holes 26 in the anchor plates 25 which not only help to secure the cord, but align the cord under the clamping screw 27 and washer 28. To adjust the straight 20 edge parallel to the boards edge, one of the screws 27 is loosened, the plate 25 slipped along the cord and secured in the desired position.

25 Figure 7 denotes one of four deep grooved sheaves positioned in each corner of and under the surface of the board, to carry the harness cord, sunk into the board to avoid any interference to storage or drafting. The sheaves turn freely on the screw studs 29 which are firmly held in the board by the shoulder of said screw, the 30 clamping washer 30 and the nut 31.

The tension of the cord 32, Figure 4, is retained fixed by the spiral spring 33, this cord and spring as well as all parts of the harness hang completely housed within the under surface of the 35 board.

What I claim is:—

1. A portable drafting table comprising a board having edge recesses formed in one face and located at opposite ends thereof and diagonal recesses formed in said face and each connecting opposite ends of said edge recesses, a continuous flexible member positioned within said edge and diagonal recesses, supporting means for said continuous flexible member, a straight edge positioned upon the opposite face of said board and provided with offset end portions overlying portions of the edge recesses, and means carried by the offset end portions of said straight edge and located substantially within the plane of the edge recesses for clamping said continuous flexible member to each offset end portion.

2. A portable drafting table comprising a board having one continuous plane surface and having the opposite face thereof provided with edge and

diagonal recesses extending below the normal plane of said face, said diagonal recesses each communicating with opposite ends of said edge recesses, a sheave located adjacent to the point of connection of each diagonal recess with one of said end recesses and so positioned as to support a continuous flexible member located within said diagonal and end recesses, a continuous flexible member positioned within said diagonal and end recesses and movably supported by said sheaves, a straight edge positioned upon and adapted for straight line rectilinear movement relative to the continuous plane surface of said board, said straight edge being provided at opposite ends thereof with offset portions extending substantially within the common plane of said edge recesses, and means carried by each of said offset end portions for securing clamping engagement with said continuous flexible member at spaced points to insure straight line rectilinear movement of said straight edge relative to the plane surface of said board upon movement of said continuous flexible member about said sheaves.

3. A drafting table comprising a board having a continuous plane front surface and a rear surface provided with open edge and diagonal recesses formed therein, said open edge recesses being located at opposed ends of said board and having the opposite ends thereof connected by said open diagonal recesses, means located adjacent to the point of connection of each edge recess with one of said diagonal recesses for supporting a continuous flexible member for travel along a closed path formed by said edge and diagonal recesses, a straight edge slidably mount-

ed upon the continuous plane front surface of said board and provided with offset end portions extending substantially within the plane of said recesses, and means carried by each of said offset end portions for clamping said offset end portion to said continuous flexible member throughout substantially the entire extent of said offset end portion, whereby substantially complete uniformity of movement of said straight edge is insured upon movement of said continuous flexible member about its supporting means.

4. A portable drafting table comprising opposite plane surfaces spaced from each other a substantially uniform distance throughout the major portions of their extent, one of said surfaces being continuously plane throughout and the other of said surfaces being provided with open recesses located adjacent its opposite ends and open diagonal recesses connecting opposite ends of said first named recesses, a continuous flexible member positioned within the said recesses and mounted for travel in the same direction and at a uniform speed within both of said end recesses upon movement of said flexible member along the path defined by said recesses, means providing rolling supports for said flexible member, a straight edge mounted upon the continuously plane surface of said table and provided with end portions extending substantially within the plane of said recesses, and means carried by each offset end portion of said straight edge for securing the same to said flexible member at spaced points whereby variations in the angular movement of said straight edge relative to the plane surface of said table are avoided.

OSWALD FISHER.
